UNITED STATES PATENT OFFICE.

WILLARD F. RICHARDS, OF BUFFALO, NEW YORK, ASSIGNOR TO THE GOULD COUPLER COMPANY, OF NEW YORK, N. Y.

LOCOMOTIVE-TENDER COUPLING.

SPECIFICATION forming part of Letters Patent No. 613,313, dated November 1, 1898.

Application filed April 18, 1898. Serial No. 677,972. (No model.)

To all whom it may concern:

Be it known that I, WILLARD F. RICHARDS, a citizen of the United States, residing at Buffalo, in the county of Erie and State of New 5 York, have invented new and useful Improvements in Locomotive-Tender Couplers, of which the following is a specification.

This invention relates to a car-coupler designed more especially for the tenders of locomotives.

The automatic couplers now generally in use on passenger-cars are those known as the "Miller" coupler and the twin-jaw or vertical-plane type of coupler adopted by the Master Car-Builders' Association.

The object of my invention is to provide a tender-coupler which can be used interchangeably with a Miller or a Master Car-Builders' coupler, so that the tender can be coupled to 20 a car equipped with either of these couplers, and which can be quickly converted from one form to the other.

In the accompanying drawings, consisting of two sheets, Figure 1 is a side elevation of 25 my improved coupler applied to a tender in the form of a Miller coupler, the adjacent portion of the tender being shown in section. Fig. 2 is a top plan view of the coupler with the attaching-pin of the shank shown in section. Fig. 3 is a face view of the end sill of 30 the tender and the base-plate which carries the coupler. Fig. 4 is a vertical longitudinal section in line 4 4, Fig. 2. Fig. 5 is a horizontal section in line 5 5, Fig. 1. Fig. 6 is a 35 view similar to Fig. 2, showing the coupler in the form of a Master Car-Builders' coupler.

Like letters of reference refer to like parts in the several figures.

A is the end sill of a locomotive-tender. B 40 is an upright base-plate secured centrally to the face thereof by bolts b or other means and provided with a central horizontal socket B', which projects forwardly from the base-plate. This socket is stiffened by suitable 45 ribs b'.

Referring to Figs. 1 to 5, D is the draw-bar or shank of a car-coupler of the Miller type, which is pivoted at its inner end in the socket B' of the base-plate B by an upright removable pin e, passing through the shank and the top and bottom of said socket, so that the

shank is capable of swinging laterally when the nose of its hook D' is deflected by the nose of an opposing coupler in making an automatic coupling in a well-known manner. 55 The pivoted end of the shank is preferably offset or arranged on the same side of the longitudinal center line of the shank as the nose of the hook D', as shown in Figs. 2 and 5. The shank is provided on its rear portion opposite said offset end with a laterally-extending lug or arm F, to which are applied righting-springs g g'. The lug or arm F is formed with a horizontal sleeve or socket f, which receives said righting-springs, and which has 65 an internal web f'.

h is a bolt or rod passing through the sleeve f and through an opening in the web f' and attached at its inner end to the base-plate preferably by seating its head h' loosely in 70 an undercut slot or recess h², extending inwardly from the side of the base-plate B, as shown in Fig. 5, so that the bolt can be readily detached from the plate by sliding it laterally out of said recess. The righting-springs 75 g g' surround this bolt, and the inner spring bears at its ends against the web of the sleeve f and the base-plate B, respectively, while the outer spring bears at its inner end against said web and at its outer end against a nut 80 or washer applied to the bolt. When the coupler is deflected laterally in either direction, one or the other of the righting-springs is compressed, and as soon as the coupler is relieved from pressure the compressed spring 85 returns the coupler to its central position. The socket B' of the base-plate is open on that side thereof which faces the righting-springs, as shown in Figs. 3 and 5, and the shank extends through the open side of the 90 socket.

I is a guard-horn or guide arranged on the base-plate adjacent to the pivoted end of the coupler-shank and on the same side of the shank as its hook D'. This horn serves to 95 direct the hook of an opposing coupler into engagement with the coupler and assists in keeping the hooks interlocked.

Upon withdrawing the pivot-pin e the coupler D can be removed laterally from the socket 100 B' of the base-plate, together with the centering-springs g g' and the bolt h, connected

therewith, the said bolt slipping laterally out of the slot or recess in the base-plate, as hereinbefore described. A Master Car-Builders' coupler having a comparatively short shank 5 D², similar to that of the Miller coupler and carrying similar lateral righting-springs g²g³ and a supporting-bolt h³, can now be inserted in the socket of the base-plate in place of the removed Miller coupler, as shown in Fig. 6, 10 the shank of the coupler being pivoted in the socket by the same pin e and the bolt carrying the righting-springs being of the same dimensions as that of the Miller coupler and engaged with the same slotted recess h² of the base-plate. In the Master Car-Builders' coupler the short shank coincides with the longitudinal center line of the coupling, and the laterally-extending arm or lug F' which carries the bolt h³ and the righting-springs is 15 somewhat larger than that of the Miller coupler, as shown in Fig. 6. By this construction the two couplers can be interchanged as occasion may require, and as they are not attached to the tender by permanent bolts or other positive means, but by simple removable fastenings, they can be quickly and conveniently changed.

The hook of the Miller coupler may be rigid or integral with the shank, but in order 20 to facilitate uncoupling the hook is preferably pivoted thereto by an upright pin j and held in its normal position by a suitable lock, so that upon unlocking the hook it is free to swing outward out of engagement with the 25 hook of an opposing coupler. In the construction shown in the drawings the hook is provided in rear of its pivot with a tailpiece or locking-arm k, and a longitudinally-sliding lock l is employed, which engages normally 30 with the front side of said tailpiece, as shown in Fig. 5, and is yieldingly held in this position by a spring m, bearing against the rear end of the lock. The latter and its spring are seated in a longitudinal socket or cavity 35 formed in the shank of the coupler, as shown in Figs. 4 and 5. The lock is retracted by an upright bell-crank lever n, pivoted by a transverse pin n' to the upper side of the shank. The lower arm of this lever extends through 40 an opening in the top of the lock-cavity and engages in a recess in the upper side of the lock, as shown in Fig. 4, while the upper arm of the bell-crank lever is connected by a chain o with the arm p of an operating or rock-shaft 45 P, journaled transversely on the sill of the tender and having end cranks or arms for turning it. In detaching the car-coupler from the tender the pivot-pin n' of the operating-lever is removed, so as to detach the 50 lock-operating mechanism from the coupling.

The knuckle of the Master Car-Builders' coupler shown in Fig. 6 is held in its normal position by any similar lock which is operated by the same devices shown in connection with 55 the Miller coupler.

I claim as my invention—

1. The combination with a base-plate or support having a socket which is open at its side, of a removable coupler having its shank pivoted in said socket and provided with an 70 arm or lug which projects laterally through the side opening of said socket, front and rear righting-springs which bear respectively against the front and rear sides of said arm or lug, and a supporting-bolt for said springs 75 which is detachably secured at its rear end to said base-plate or support and which passes through said arm or lug and against which the front righting-spring abuts, substantially as set forth.

2. The combination with a base-plate or support, of a car-coupler having its draw-bar or shank pivoted to said base-plate or support and provided with a laterally-arranged longitudinal sleeve or socket having an internal web and righting-springs operating against opposite sides of said web, substantially as set forth.

3. The combination with a base-plate or support, of a car-coupler having its draw-bar 90 or shank pivoted to said base-plate or support and provided with a laterally-arranged longitudinal sleeve or socket having an internal web, a bolt attached to said base-plate or support and extending through said sleeve and 95 its web, an inner righting-spring applied to said bolt between the said base-plate and said web, and an outer righting-spring applied to the bolt between said web and a nut or washer on said bolt, substantially as set 100 forth.

4. The combination with a base-plate or support having a notch or recess at one side thereof, of a car-coupler having its draw-bar or shank removably pivoted to said base-plate 105 or support and provided with a laterally-projecting arm or lug, a bolt removably interlocked with the notch or recess of said base-plate and passing through said arm or lug and righting-springs applied to said bolt and 110 operating against opposite sides of said arm or lug, substantially as set forth.

5. The combination with a base-plate adapted to be attached to a tender or car and provided with a forwardly-projecting socket 115 which is open at one side, of a car-coupler having its draw-bar or shank removably pivoted in said socket by an upright pin and provided with a laterally-projecting lug or arm, righting-springs applied to the front and rear sides 120 of said lug or arm and a bolt passing through said righting-springs and said lug or arm and detachably connected to said base-plate or support, substantially as set forth.

Witness my hand this 9th day of April, 125 1898.

WILLARD F. RICHARDS.
